UNITED STATES PATENT OFFICE.

PONTUS OSTENBERG, OF LOS GATOS, CALIFORNIA.

INTERNAL-COMBUSTION TURBINE-ENGINE.

1,125,157.

Specification of Letters Patent. Patented Jan. 19, 1915.

Application filed July 8, 1913. Serial No. 777,834.

To all whom it may concern:

Be it known that I, PONTUS OSTENBERG, a citizen of the United States, residing at Los Gatos, in the county of Santa Clara and 5 State of California, have invented a new and useful Internal-Combustion Turbine-Engine, of which the following is a specification.

My invention relates to internal combustion 10 turbine engines.

One object of my invention is to provide an engine in which the driving power is produced by water under pressure of gas explosion.

15 Another object of my invention is to produce an engine in which power may be produced with a very small amount of friction and one in which the water is continuously used against the turbine wheel alternate in 20 action.

Another object of my invention is to produce an internal combustion turbine engine that may be economically constructed, simple in operation, efficient and durable, and 25 one which may be adapted to any purpose where power is required.

In the accompanying drawings, Figure 1 is a side elevation of my internal combustion turbine engine. Fig. 2 is a front elevation 30 of the same. Fig. 3 is a vertical section on line A—A of Fig. 2. Fig. 4 is a vertical section on line B—B of Fig. 2. Fig. 5 is a vertical section on line C—C of Fig. 1. Fig. 6 is a horizontal section on line D—D of 35 Fig. 2.

Similar reference numerals designate corresponding parts in all the figures of the drawings.

Referring more particularly to the drawings, my invention is described as follows:—The numerals 1 and 2 represent the body portions of my invention, the same being cast in two separate parts, and may be made of cast iron or any other suitable material 45 and bolted together by bolts shown at 3. The upper parts of said body-portions 1 and 2 are cylindrical in form, of the proper length and proper diameter and are approximately vertical in position. In the proper position 50 near the upper ends of said cylindrical portions are offsets cast therein shown at 4. In the top of said offsets 4 are placed a plurality of exhaust valves shown at 5. At the extreme top of said cylindrical portions 1 and 2 are shown intake valves 6, which are for the purpose of admitting the explosive

vapor taken in from any ordinary carbureter. Said explosive vapor may be exploded by means of a hot ball as shown at 7, or any other suitable means. Try-cocks are shown 60 at 8, which are for the purpose of designating the height of water in said cylindrical portions. Water inlet valves are shown at 9 which are for the purpose of admitting water to said cylindrical portions, 1 and 2. 65 The body portions 1 and 2 are cast in separate parts, the base being in the form of a scroll as shown at 10, Figs. 1 and 3, leaving a hollow space therein into which is placed a turbine wheel 11, said wheel being keyed 70 to shaft 12, said shaft 12 resting in bearings 13. Inside of said base and in each section thereof are cast partitions 14 having ports 15 slanting inwardly through said partitions as shown in Figs. 3, 5, and 6, 75 and are for the purpose of directing the force of the water against the vanes 16 on turbine wheel 11, in either direction driving said turbine wheel 11 always in the same direction, said vanes 16 being 80 supported by an outer rim 16a. At the lower parts of said cylindrical portions 1 and 2 is cast a port 17. Said port is opened and closed by a valve shown at 18 and is for the purpose of governing the speed of said 85 turbine wheel 11. Said valve 18 is operated by any suitable connection attached to valve-stem 19.

The operation of my engine is as follows:—The cylinders are filled with water 90 through inlet valve 9 to the level of try-cock 8. A charge of gas is admitted to the upper portion of each cylinder through any ordinary carbureter. The charge of gas in one cylinder is then exploded, said explosion 95 forcibly driving the water downward in that cylinder and through all of the ports on that side of the turbine wheel, against the vanes of the turbine wheel and up through the ports in the scroll of the second cylinder. 100 The body of water ascending in the second cylinder compresses the gas in said second cylinder which, when exploded, drives the body of water back through its ports against the vanes of the turbine wheel and back 105 through the ports in the first cylinder. The parts of this engine are so proportioned that when the water is driven from one cylinder by the gas explosion it causes a vacuum and a fresh charge of gas is drawn in through 110 inlet valve 6 to fill that portion of the cylinder above the exhaust valves. When the

water returns to the cylinder after each explosion it drives the exhaust out of said cylinder through the exhaust valves 5 until the water itself reaches and closes said valves 5 when the charge of gas in that portion of the cylinder above the exhaust valves is compressed and exploded and the operation is alternately repeated. The gas and air mixture will not explode until the same 10 has been compressed, and this compression does not occur until after the expanded gases have been discharged through valves 5 and the onrushing water has closed valves 5, continuing on upward to compression. Valves 15 5 are so balanced that they will lift just enough to allow the expanded gases to escape therethrough, and close instantly when the water reaches them. When the compressed 20 gases are exploded by hot ball 7 the exhaust valves 5 are closed on their lower seats. As the water descends with force by said explosion it forms a vacuum which causes said valves 5 to take their upper seats, and by this same vacuum a fresh charge of gas and 25 air mixture is drawn into the upper part of the cylinder above the exhaust valves 5 through valve 6, operating alternately. It is shown by experience that the expanding gases operating as above stated do not mix 30 with the fresh charge drawn in to the upper part of said cylinders to any extent, as the exhaust valves 5 operate quickly and discharge the expanded gases without any loss of water through said exhaust valves 5. To 35 reduce the speed of the turbine wheel the valve 18 is opened a distance and the supply of gas reduced thus driving a portion of the water through the passage 17 with reduced force and diminishing both the quantity 40 and force of the water driven against the turbine, but not changing the compression in the upper part of the cylinder.

Having thus fully described my invention what I claim as new, and desire to secure by 45 Letters Patent, is:—

1. In an internal combustion turbine engine the combination of two cylindrical portions, means of fastening the same together at their base, means for admitting water to

said cylindrical portions, means for designating the height of water in said cylindrical portions, offsets cast near the upper ends of said cylindrical portions, a plurality of exhaust valves located therein and at the top of said offsets, explosive vapor intake 55 valves at the top of said cylindrical portions, means attached to the top of said cylindrical portions to explode said explosive vapor, and a turbine wheel revolvably positioned in the base of said turbine engine and means by 60 which water is directed against said turbine wheel in opposite directions driving said turbine wheel continuously in the same direction, as shown and described.

2. In an internal combustion turbine engine of the class described, two cylindrical portions cast separate and having a base in the form of a scroll, and a hollow space therein into which is placed a turbine wheel resting on and keyed to a turnable shaft, 70 said shaft resting in bearings in said base, each section of said base having a partition through which are cast ports slanting inwardly through which water is directed against the vanes of the turbine wheel alternately in either direction, driving said turbine wheel continuously in the same direction, 75 said vanes on said turbine wheel being supported by an outer rim, substantially as specified.

3. In an internal combustion turbine engine of the class described, two cylindrical cast portions bolted together at their base in which is placed a turbine wheel having vanes against which water is forced alternately in 85 either direction, driving said turbine wheel continuously in the same direction, a passage connecting said cylindrical portions, said passage being opened and closed by a valve as shown, by which the speed of said turbine 90 wheel is governed, substantially as specified.

In testimony whereof I have signed my name to this specification in the presence of two subscribing witnesses.

PONTUS OSTENBERG.
